UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

METHOD OF UNITING FABRIC SECTIONS.

1,349,712.

Specification of Letters Patent. Patented Aug. 17, 1920.

Application filed December 30, 1916. Serial No. 139,822.

To all whom it may concern:

Be it known that I, JOSEPH BERGER, Jr., a citizen of the United States, residing at Utica, in the county of Oneida, State of New York, have invented certain new and useful Improvements in Methods of Uniting Fabric Sections, of which the following is a description, reference being had to the accompanying drawing and to the figures of reference marked thereon.

The invention relates to new and useful improvements in the method of uniting fabric sections, and more particularly to the method of attaching fabric sections to form a flat covered seam.

An object of the invention is to provide a new method of forming covered lapped seams wherein the edges of the fabric sections are simultaneously trimmed as they are stitched and wherein the said edge portions are lapped so that said trimmed edges terminate within the limits of the stitching mechanism, whereby the overlapped sections will be penetrated by a central needle of the stitching mechanism, and said trimmed edges covered by the stitching threads.

In the drawing:

Figure 1 is a perspective view showing certain parts of a sewing machine which may be used in carrying out the invention;

Fig. 2 is a perspective view showing the steps in the method whereby the fabric sections are united;

Fig. 3 is a plan view of the same;

Fig. 4 is a sectional view through a throat plate and presser foot, showing more or less diagrammatically the trimming blades, the needles, and the looper which co-operates with the needles, the edge portions of the fabric sections being turned up for trimming;

Fig. 5 is a sectional view through the throat plate and the presser foot, showing also the needles and showing the edge portions trimmed and the means for crowding one of the trimmed edge portions underneath the other;

Fig. 6 is a sectional view through the throat plate and the presser foot, showing the fabric sections overlapped and the needles which are about to enter the fabric sections; and

Fig. 7 is a diagrammatic view showing the overlapped edge portions of the fabric sec-

tions and the relation of the stitching threads thereto.

The invention is directed broadly to a new method of joining fabric sections wherein the edge portions of the fabric sections are united by a stitching mechanism forming three parallel rows of needle thread loops connected above and below the fabric sections to form covering stitches and said edge portions are trimmed in advance of and simultaneously with the stitching of the seam, so that said edge portions will terminate in overlapped relation and within the limits of the outer rows of needle thread loops and be penetrated by the central row of needle thread loops, whereby the overlapped edge portions will be joined and the trimmed edges thereof covered by the stitching threads.

The invention resides particularly in the order of events, that is, the trimming of the edge portions simultaneously with the stitching thereof, and in the trimming of the edges so as to bring about an overlapping of the fabric sections within the limits of the stitching mechanism whereby the results referred to above are accomplished. In the drawings, I have illustrated one method of carrying out the invention, and it is possible that the invention will be more clearly understood by reference thereto.

The fabric sections to be joined are indicated at F and F', respectively. These fabric sections are brought together and their edge portions f and f' turned up out of the plane of the fabric sections, as clearly shown in Figs. 1 and 2.

The sewing machine parts illustrated in the drawings consist of a presser foot 1 having a slot 2 at its forward end into which the up-turned fabric sections are directed. The trimming mechanism consisting of a fixed trimming blade 3 and a movable trimming blade 4 operates to trim the upturned edge portions. After the upturned edge portions have been trimmed, a guiding member 5 on the presser foot crowds the trimmed edge portion f back into the plane of the fabric F and underneath the edge portion f' which is held raised by a rib 6 on the throat plate. The rear end wall of the slot 2 in the presser foot then serves to turn down the edge portion f' so that the two edge portions are overlapped, as clearly shown in the draw.

ings. This turning down of the edge portion f' brings it into the plane of the fabric section F'.

The stitching mechanism, as shown in the drawings, consists of three needles 7, 8 and 9. The thread hook 10 engages a cross thread which extends through a fixed thread guide 11 and forms a loop therein for certain of the needles to enter so that the 10 needle threads on the upper face of the fabric are connected by a cross thread. The thread of the needle 7 is indicated at 7^a; the thread of the needle 8 is indicated at 8^a; and the thread of the needle 9 is indicated 15 at 9^a, while the cross thread is indicated at 10^a. Beneath the work support there is a single looper 12 which enters all of the needle thread loops, and this looper carries a looper thread 12^a which joins all the 20 needle loops beneath the fabric. The throat plate 13 has the rib 6 formed therein which directs the upturned edge portions of the fabric sections. The surface 14 of the throat plate, which supports the fabric section F, 25 is in a lower plane than the surface 15 which supports the fabric section F'. The upturned edge portions are slightly at one side of the center needle, as clearly shown in Fig. 4 of the drawings, and this arrangement greatly facilitates the turning of the 30 edge portion f under the edge portion f' , and also insures that while the overlapped portions of the fabric sections are wholly within the limits of the stitching mechanism, yet the extreme edges of the fabric sections lie close to the points where the 35 respective outer needles penetrate the fabric sections.

From the above, it will be apparent that 40 my improved method for joining fabric sections consists in the simultaneous trimming of the edge portions of the fabric sections and the stitching of the same, and it is through the trimming action that the edge

portions are overlapped with the trimmed 45 edges within the limits of the threads of the stitching mechanism. After the edges have been trimmed and overlapped to the proper distance, then these overlapped edges are 50 united by stitching, the center line of 55 stitches passing through the overlapped portions of the fabric, while the outer lines of stitches pass through the respective fabric sections only and close to the trimmed edges. The cross thread and the looper thread connecting the needle threads not only aid in joining the fabric sections, but cover the 60 trimmed edges of the fabric sections.

It will be obvious that minor changes in the steps of the method described in detail 65 above may be made without departing from the spirit of the invention which it set forth in the appended claim.

Having thus fully described the invention, what is claimed as new is:—

The method of forming a covered lapped seam consisting in uniting the edge portions 70 of fabric sections to form the seam by a stitching mechanism forming three parallel 75 rows of needle thread loops connected above and below the fabric sections to form covering stitches and trimming both edges in advance of and simultaneously with the stitching of the seam, so that said edge portions will terminate in overlapped relation and within the limits of the outer rows of needle thread loops and be penetrated by the central row of needle thread loops, whereby the overlapped edge portions will be joined and the trimmed edges thereof will be covered 80 by said threads.

In testimony whereof I affix my signature, in the presence of two witnesses.

JOSEPH BERGER, Jr.
